UNITED STATES PATENT OFFICE.

GEOERGE HENRY WHEARY, OF RACINE, WISCONSIN.

TRUNK-FITTING.

1,118,982.

Specification of Letters Patent.

Patented Dec. 1, 1914.

Application filed March 14, 1913. Serial No. 754,184.

To all whom it may concern:

Be it known that I, GEORGE H. WHEARY, a citizen of the United States, and resident of Racine, in the county of Racine and State 5 of Wisconsin, have invented new and useful Improvements in Trunk-Fittings, of which the following is a description, reference being had to the accompanying drawings, which are a part of this specification.

10 This invention relates to improvements in trunk fitting for trunks of that type in which the trunk is adapted to stand on one end and is divided vertically, medially into two sections which are covered by a top or end 15 cover. In trunks of this type it is very desirable to securely bind the different parts together in order to prevent torsional strain or working of the parts with relation to each other and bind the parts, when in closed 20 position, into a rigid structure.

It is one of the objects of this invention to provide a trunk fitting which is adapted to bind the adjacent sections of a trunk, of the before mentioned type, together so that 25 they will resist twisting or torsional strains and cannot work with relation to each other.

A further object of the invention is to provide a trunk fitting which is so constructed as to automatically lock the sections of the 30 trunk together when the said sections are swung to closed positions.

A further object of the invention is to provide a trunk fitting which is of very simple construction, is well adapted for the 35 purpose desired and which may be manufactured at a minimum cost.

With the above and other objects in view, the invention consists of the improved trunk fitting and its parts and combinations as set 40 forth in the claims, and all equivalents thereof.

In the accompanying drawing in which the same reference characters indicate the same parts in all of the views: Figure 1 is a 45 side view of the upper portion of a trunk provided with the improved trunk fitting, the cover of the trunk being also indicated in open position by dotted lines; Fig. 2 is an enlarged side view of the lower parts of 50 the fitting shown attached to portions of a trunk, a portion of the fitting being in section, the view also indicating the wardrobe section as being in partly open position by dotted lines; Fig. 3 is a rear view of the fitting; and Fig. 4 is a top view of the lower members of the fitting.

Referring to the drawing the numeral 8 indicates the body section, 9 the wardrobe section and 10 the cover section of a wardrobe trunk of the type for which the improved fitting is particularly adapted for use in connection therewith.

The improved fitting 11 attached to the trunk comprises the upper or cover member 12 and the two lower members 13 and 14 which are attached respectively to the wardrobe section and to the body section of the trunk. The fitting is stamped from sheet metal and when assembled is of approximately rectangular form and has a medially positioned outwardly projecting annular rib 15 raised therefrom which forms the locking means of the fitting and also gives an ornate appearance to the fitting. The fitting is divided horizontally, centrally to 75 form the upper member 12 and the lower half of the fitting is divided vertically, centrally to form the two lower members 13 and 14. The lower member 14 is provided with a projecting tongue 16 which is adapted to enter the recess 17 of the member 13, the recess being formed by the raised portion of the fitting and the outer face of the wardrobe section of the trunk. The upper member is also provided with projecting tongues 18 which enter the recesses 19 and 20 respectively of the lower members 13 and 14 and lock the two said lower members securely together. All of the tongues are of sufficient size to fit the recesses snugly and are tapered toward their advancing ends to 80 easily enter the recesses. The tongues are also offset inwardly from the outer surface of the rib to provide for the outer surfaces of the portion of the rib of each member being in alinement with relation to each other portion.

From the foregoing description it will be seen that the trunk fitting when mounted upon a trunk and in closed position will 100 securely lock the three portions of the trunk together and that the lower trunk sections cannot be opened until the trunk cover has been swung to open position.

What I claim as my invention is:

1. A trunk fitting, consisting of a three part member provided with means for locking two of the parts together while the said two parts are engaged by the third part, each one of said parts having a locking 110 means forming relatively an immovable portion of said part.

2. A trunk fitting, consisting of a three part member having a tongue and recess engagement with each other to lock two of the parts together by the engagement of the third part with said two parts.
3. A trunk fitting, comprising an upper member provided with a pair of tongues, a lower member provided with a recess and a projecting tongue, and another lower member provided with a pair of recesses one of which is entered by the tongue of the other lower member, each tongue of the upper member entering one recess of one of the lower members to lock said lower members together.
- 10 4. A trunk fitting, comprising an upper member provided with a pair of tongues projecting from its lower edge, a pair of

lower members having an edge to edge engagement with each other and with the upper member, said lower members provided with a tongue and recess engagement with each other and said lower members provided with recesses into which the tongues of the upper member extend, the three members being reinforced by an annular rib embossed from said members which rib is in circumferential alinement with the tongues and recesses of the members.

20 25 In testimony whereof, I affix my signature, in presence of two witnesses.

30 GEORGE HENRY WHEARY.
